UNITED STATES PATENT OFFICE.

FREDERICK A. WATKINS, OF CHICAGO, ILLINOIS.

SOUND TRANSMITTER.

Application filed June 22, 1923. Serial No. 647,005.

To all whom it may concern:

Be it known that I, FREDERICK A. WATKINS, a citizen of the United States, and a resident of Chicago, in the county of Cook and State of Illinois, have invented certain new and useful Improvements in Sound Transmitters; and I do hereby declare that the following is a full, clear, and exact description thereof, reference being had to the accompanying drawings, and to the characters of reference marked thereon, which form a part of this specification.

This invention relates to improvements in sound transmitters adapted for use with telephone transmitters and like instruments of that kind including within the mouthpiece of the transmitter, and in front of a diaphragm constituting part of the transmitter, a receptacle to confine a body of air which lies against the diaphragm, the said receptacle serving, in addition to its function of confining the body of air, as a means to deflect against the diaphragm sound waves which would otherwise be dissipated outwardly and result in a partial loss of power to vibrate the diaphragm. The result is that the diaphragm can be efficiently vibrated by small vibrations produced by low or so-called whispering tones.

Among the objects of the invention are to improve the transmitting effects of such an imprisoned body of air and the reflecting effects of the receptacle which retains the body of air, so as to produce, with greater sharpness, the tone effects of low vibrations at a receiving instrument constructed to transmute vibrations into sound waves.

Other objects of the invention are to otherwise improve, simplify and reduce the cost of the construction of such a device, and the invention consists in the elements and combination of elements shown in the drawings and described in the specification, and is pointed out in the appended claims.

In the drawings:

Figure 1 is a side elevation of a transmitter embodying my invention.

Figure 2 is an axial section thereof.

Figure 3 is a front view of the ring member clasp and receptacle with the mouthpiece omitted.

Figure 4 is a side elevation of the air body confining receptacle and the means for holding it in place.

Figure 5 is a side elevation of the air body

confining receptacle and sound wave reflector.

The invention will be described in connection with a known telephone transmitter for the purpose of readily understanding the purpose and function thereof, but said invention may be embodied in transmitters for other uses.

The bell-shaped mouthpiece 10, which can be made of glass or other suitable material, is exteriorly formed at its rear, smaller end with an annular rib 11 that surrounds the open rear end of the mouthpiece. Said flanged end of the mouthpiece fits with a snap action into a clasp designated as a whole by 12. The said clasp is of ring-like formation and is preferably made of resilient sheet metal. It is slotted to produce clasp fingers 13 which are shaped at their outer ends to readily receive the flange 11 to permit it to be snapped into and removed from the clasp.

14 designates a ring member which is formed with a rearwardly extending tubular, exteriorly threaded portion 15 to fit within a threaded opening of the wall of a box or chamber which, in practice, supports the diaphragm 16. Said ring member 14 has a radial flange 17 to which the clasp member 12 is fitted and attached. As herein shown, the flange 17 is provided radially within its margin on its outer face with a recessed seat 18 to receive an annular in-turned flange 19 of the clasp 12 which lies flat against said seat, with its internal edge abutting an annular shoulder between said seat and the deeper front face 18' of said ring member. Said clasp is fastened to said ring member by radially expanding the portion 18' of the ring member that lies between the bore of the ring member and said recess. The said ring member may be expanded by a tool having radial ribs to produce the radial indentation 17' shown in Figure 3. Said tool is thrust axially against the ring member, and confines the metal thereof from endwise displacement and thereby expands the metal of the ring member both inwardly and outwardly against the inner edge of the flange 19 and towards the receptacle 20 to cause the metal of the ring member to tend to flow over said edge and against the base of said receptacle to hold said parts in place.

20 designates a receptacle which is lo-

cated axially in said mouthpiece and the mounting ring 14. It is made of sheet metal by suitable swaging operation, and is closed and internally conoidal at its outer end and externally cylindric at its inner end. The external diameter of the rearmost cylindric portion 21 of said receptacle is such as to be pressed with a close fit into the bore of the mounting ring 14 and is held therein by such fit. The exterior diameter of said receptacle is slightly less than the interior diameter of the smaller, rear part of the mouthpiece 10 so as to provide an annular passage 22 for sound waves coming from the forward larger end of the mouthpiece. The receptacle is provided near its base portion with a plurality of openings 23 which communicate with the annular passage 22 to carry the sound waves backwardly through the rear hollow base of said receptacle to the diaphragm 16.

The said receptacle 20 is formed to produce an internal conoidal face 24 at its forward end and is closed from its extreme forward end back to the margins 25 of the openings 23 so as to form a chamber 26 within which, and between the bounding walls of the chamber and the diaphragm, a body of air is confined.

In accordance with one phase of the invention, the length of said receptacle 20 from the outer margins 25 of the openings 23 to the inner conoidal face of the outer end of the receptacle is not less than the internal diameter of the casing at said openings 23 and at the base 21 of the receptacle. I find in practice that superior results are obtained by making the axial dimension referred to about twenty-five per cent greater than the said internal diametric dimension. This appears to be due to the fact that the pressure undulations of a confined air body of comparatively long length, relatively to its diameter, produced by sound waves projected through the flaring mouthpiece, around and through the receptacle to the diaphragm, and the rebounding effect of the sound waves, due to the conoidal ended portion of the receptacle, has the effect of increasing the pressure of the confined air body beyond normal, under the control of direct and rebounding sound waves, and that said pressure acts against said diaphragm with increased force to produce good sound wave definition characteristics.

From what has been said in connection with the drawings, it will be clear that the construction of the transmitter, both with respect to the manufacture of its elements and the assemblage thereof, is economical and the resultant device is simple and sturdy.

The part 21 of said receptacle constitutes a tubular anchor which can be forced into

the ring 14 either before or after the ring is assembled with the mouthpiece and its clasp, it being practical and preferable to insert said receptacle in place through the rear end of said ring member.

70

I claim as my invention:

1. A sound transmitter comprising a mouthpiece having a smaller end, and means within said mouthpiece and anchored within its smaller end to confine a body of air in front of the diaphragm of a length greater than the diameter of said body, the anchor comprising a tubular extension to constitute an enclosed sound passage and closely fitting within the smaller end of the mouth piece, the sound passage internally communicating with said mouthpiece and with the interior of said air confining means.

2. A sound transmitter comprising a flaring mouthpiece adapted at its smaller open end to face a diaphragm and means insertable within said smaller end to confine a body of air a distance in front of the diaphragm and of an air confining length substantially greater than the diameter of said body.

3. A sound transmitter comprising a flaring mouthpiece adapted at its smaller end to face a diaphragm and an air confining receptacle within the smaller end of said mouthpiece having a rearwardly extended tubular anchor extension constituting a sound passage arranged to produce therearound a continuous annular sound wave passage, said receptacle having an opening in its circumferential wall abreast and communicating with said sound passage.

4. A sound transmitter comprising a flaring mouthpiece adapted at its smaller end to face a diaphragm and an air confining receptacle within the smaller end of said mouthpiece arranged to produce therearound an annular sound wave passage, said receptacle having an opening in its circumferential wall abreast said sound passage and extending rearwardly from said opening to constitute a hollow cylindric anchor extension.

5. A sound transmitter comprising a flaring mouthpiece adapted at its smaller end to face a diaphragm and a combined sound reflector and air body retainer within said mouthpiece open at its rear end and closed at its front end, and provided with a solid tubular anchor extension constituting an enclosed sound passage arranged to form a continuous annular sound wave passage between it and said mouthpiece, and provided in front of said extension with a circumferential opening communicating with said passage.

6. A sound transmitter comprising a flaring mouthpiece adapted at its smaller end to face a diaphragm and a combined sound reflector and air body retainer within said

- mouthpiece open at its rear end and closed at its front end and having at its rear end an interiorly and externally cylindric anchor extension, and arranged to form an annular 5 sound wave passage between it and said mouthpiece, and provided abreast said passage with circumferential openings communicating with said passage, the internal length of said receptacle from the outer end 10 thereof to said circumferential openings being not less than the internal diameter of said receptacle.
7. A sound transmitter comprising a flaring mouthpiece, a ring base on which the 15 smaller end of the mouthpiece is mounted, and an elongated tubular air body retaining and reflector shell open at its rear end and closed at its front end and extending into and enclosed by said ring base.
- 20 8. A sound transmitter comprising a flaring mouthpiece, a ring base on which the smaller end of the mouthpiece is mounted, and an elongated tubular air body retaining and reflector shell open at its rear end 25 and closed at its front end and extending into and enclosed in said ring base and forming between it and the smaller end of the mouthpiece a sound wave passage and abreast said passage with circumferential 30 openings.
9. A sound transmitter comprising a ring base provided with a mouthpiece mounting and a receptacle open at its rear end and closed at its front end and having a close 35 fit connection to said ring base.
10. A sound transmitter comprising a ring base and provided with a mouthpiece mounting and a receptacle open at its rear end and closed at its front end and having a close 40 fit connection to said ring base, said receptacle being provided in front of said ring base with a circumferential opening.
11. A sound transmitter comprising a ring base and provided with a mouthpiece 45 mounting and a receptacle open at its rear end and closed at its front end and having a close fit connection to said ring base, said receptacle being provided in front of said ring base with a circumferential opening, the internal diameter of said receptacle 50 at said circumferential opening being less than the axial dimension thereof from said circumferential opening outwardly to the closed end of said receptacle.
12. In a sound transmitter a combined air 55 body retainer and sound wave reflector receptacle, said receptacle having a cylindric anchor part at its rear end and closed at its forward end and provided in its wall between its ends with a radial opening extending through the wall from the inner to the outer part of said retainer.
13. In a sound transmitter a combined air body retainer and sound wave reflector receptacle, said receptacle being formed at 60 its rear end with a cylindric anchor end and closed at its forward end and provided between its ends with a radial opening extending radially through said retainer, the length of said reflector from its closed end 65 to said radial opening being greater than the internal diameter of said receptacle.
14. A sound transmitter comprising a ring base formed at its forward side with a mouthpiece clasp and a sound wave confining and reflecting receptacle formed at its rear end 70 to constitute an anchoring extension telescopic in the ring base in rear of said mouthpiece mounting.
15. A sound transmitter having an axial 75 bore and forward thereof a mouthpiece mounting and a hollow sound wave confining and reflecting receptacle having a cylindric open base fixed in said bore and having forwardly therefrom a closed internally conoidal reflecting face.
16. A sound transmitter having an axial 80 bore and forward thereof a mouthpiece mounting and a hollow sound wave confining and reflecting receptacle formed with 85 a cylindric open base having a close fit in said bore and extending forwardly therefrom and formed with a closed end, and a mouthpiece fixed to said clasp and enclosing said receptacle, between which and said 90 receptacle a sound wave passage is formed that communicates with the rear hollow end of said receptacle.
- In witness whereof I claim the foregoing as my invention, I hereunto append my signature this 11th day of June, 1923.
- FREDERICK A. WATKINS.
